This invention relates to voltage regulator systems and more particularly to a transistor voltage regulator incorporating means for protecting a control transistor of such a system from overloading under abnormal operating conditions.

There are numerous applications in which it is desirable to provide a relatively constant direct current output voltage regulated against variations in input voltage and against changes in load. One system for such use employs a control transistor connected so that its bias voltage is controlled by the difference between a constant reference voltage and the output voltage. Changes in output voltage thus produce a biasing signal varying the conductivity of the transistor. Such conductivity variation is used in various ways to restore the output voltage to its predetermined value. Under abnormal operating conditions, such as those produced by a total or partial short circuit across the load, the temporary drop in output voltage and the corresponding increase in voltage drop across the regulator is quite substantial. The decrease in output voltage is accompanied by a corresponding increase in output current with the result that there is a corresponding increase in the conductivity of the transistor and in the amount of power it must dissipate. In many instances, the power increase is so large it may cause the transistor to become overheated and break down resulting in failure of the regulator system.

The use of conventional protective devices, such as thermally operated switches, for this purpose has not been entirely satisfactory since such means are generally too slow acting to be effective. Conventional protective devices are also generally incapable of distinguishing between abnormal conditions, such as short circuits, and voltage changes the regulator is suited for controlling. Where a protective element serves to disconnect a regulating transistor from the circuit, it should be capable of restoring operative connection quickly and automatically once the abnormal condition terminates.

It is an object, therefore, of the present invention to provide a voltage regulator system incorporating instantaneously effective protective features to prevent overloading of a control element subject to breakdown.

It is a further object of the invention to provide a transistor voltage regulator system which protects the control transistor against overloading of the type caused by short circuits across the output terminals.

It is another object of the invention to provide a transistor voltage regulator effective to discriminate between temporary abnormal operating conditions such as short circuits and other changes in operating conditions which the system is capable of regulating without danger of destruction of the control transistor.

A feature of the present invention is the provision of a device sensitive to simultaneous changes in output voltage and output current so that a voltage regulating element is bypassed upon the occurrence of a short circuit across the load of the system.

Another feature of the invention is the combination of a switching transistor coupled to one side of a reference voltage element of a voltage regulator and connected to become conductive upon a simultaneous increase in output current and decrease in output voltage to the end that the reference voltage supplied is decreased and the voltage regulating transistor of the system is prevented

from being thrown into conduction under conditions which might damage it.

A further feature of the invention is the provision of a switching transistor having a pair of resistors connected serially between its base and emitter and with the voltage derived across such resistors, which controls conduction of the transistor, being responsive to changes in output current and voltage. The polarity of the voltage vectors derived across the resistors are opposing so that their algebraic sum becomes sufficient to cause conduction to take place instantly when the output voltage drops and the output current rises at the same time, and upon termination of this condition, the voltage applied to the switching transistor immediately drops to a value rendering it non-conductive and reactivating the regulator portion of the system.

The accompanying single FIGURE of drawings is a circuit diagram of a transistor voltage regulator embodying the protective features of the present invention.

In accordance with the invention, a direct current voltage regulator includes control means such as a transistor having its base coupled to a reference voltage element and having its emitter and collector connected across a resistor in series in the line to be regulated. A second transistor is connected to one side of the reference voltage element and is connected in circuit so that its base to emitter bias voltage is the algebraic sum of signal voltages of opposite polarity, one of which reflects output voltage of the system and the other of which reflects its output current. When the output current rises and the output voltage drops simultaneously, as when there is a partial short circuit across the load of system, the switching transistor is thrown into conduction thus effectively unclamping the side of the reference voltage element to which it is connected in common with the base of the first transistor and decreasing the reference voltage. Since the control transistor becomes conductive only in response to a difference signal between the output voltage and the reference voltage, simultaneous decrease in these two voltages prevents the difference signal from becoming large enough to throw the control transistor into conduction. In this way, the control transistor is protected from being thrown into conduction under abnormal and potentially destructive operating conditions.

The series voltage regulator system illustrated includes input terminals 11 and 12 connected to an unregulated D.C. voltage source and output terminals 13 and 14 across which a load indicated by the resistor 16 is connected. The control section of the system includes the p-n-p transistor 17 having base 18, collector 19, and emitter 21. The emitter-collector circuit of the control transistor is connected across the series resistor 22.

The voltage reference section includes the voltage reference element 23 and the resistor 24 connected in series across the input terminals 11 and 12. The reference element 23 is shown as a Zener diode which is a convenient and effective component for providing a constant reference voltage. It will be understood, however, that other reference voltage elements, such as batteries, may be substituted therefor in some embodiments of the invention, provided they serve the function of providing a constant voltage drop.

The Zener diode 23 is effective to clamp the point 26 at a constant potential and the base 18 of the transistor 17 is connected to this point. This controls the conductivity between the collector 19 and emitter 21 to provide regulating action as will be further described.

The protective portion of the system is made up of the switching transistor 27 which is illustrated as a p-n-p unit. The polarity of the output voltage may be reversed from that shown, if desired, by substituting n-p-n units

for the transistors 17 and 27. The transistor 27 may be the same type of transistor as the control or regulating unit and both are typically alloyed junction devices. Transistor 27 includes base 28, collector 29, and emitter 31. Emitter 31 is connected between the resistors 32 and 33 which form a voltage divider across the output terminals of the system. A resistor 34 of relatively low ohmic value is connected in series with resistor 33 between base 28 and emitter 31 of the switching transistor.

During normal conditions of operation, the point 36 to which the emitter 31 is connected is substantially more negative than the point 37 to which the base 28 is coupled. This results in reverse biasing of the emitter-base junction of the transistor 27 so that the unit is non-conductive and effectively out of the circuit. Under these conditions, the voltage drop, designated as E_4 , across the Zener diode 23 is a constant value so that the point 26 is clamped at a fixed potential. The base to emitter bias voltage of the regulator control transistor 17 is thus equal to the difference between the reference voltage E_4 and the output voltage E_3 . When E_3 drops below E_4 , the resultant difference signal applies a bias which effectively decreases the collector to emitter resistivity of transistor 17. This causes less current applied at input terminal 11 to flow through the shunt resistor 22 thus decreasing the voltage drop E_2 across the shunt resistor and tending to restore the output voltage E_3 to its regulated value, i.e. the reference voltage E_4 . The value of resistor 22 is chosen so that the maximum input voltage available will be dropped to the desired output value under conditions of anticipated minimum current drawn through the load. Operation of the system under normal conditions wherein the input voltage and/or load vary is well known and will not be described in further detail.

Under abnormal conditions of operation, such as occur when there is a total or partial short circuit across the output load 16, the output voltage E_3 will drop to a very low value so that the difference voltage $E_4 - E_3$ applied across the base-emitter connection of transistor 17 is quite large. There is a corresponding increase in the current I_1 through the control transistor 17 due to its sharp increase in conductivity. At the same time, voltage drop E_2 increases since E_2 is equal to the input voltage E_1 minus the output voltage E_3 . The power dissipation in transistor 17 is equal to the product of E_2 and I_1 so that an increase in both these quantities simultaneously produces a very substantial amount of heat. In many instances, this heat cannot be dissipated adequately so that it raises the temperature of the transistor 17 to the extent that breakdown takes place and the system becomes inoperative.

The present invention solves the problem of damage to regulating transistors under such conditions by means of the protective circuit including the switching transistor 27. This transistor is connected so as to effectively sample both the output voltage E_3 and the output current I_2 of the system. When a short circuit occurs in the load 16, the voltage drop across resistor 33 decreases in proportion to the drop in output voltage. At the same time, the voltage drop across resistor 34 increases due to the increase in output current I_2 flowing therethrough. The voltage drops developed across resistors 33 and 34 are of opposite polarity (as indicated by the voltage vector arrows) and, since they are connected between base 28 and emitter 31, the bias voltage controlling the conductivity of switching transistor 27 is increased, being the algebraic sum of the two developed voltages. In other words, the point 36 to which emitter 31 is connected becomes less negative while the point 37 to which the base 28 is connected becomes more negative. At the point where the base connection is negative with respect to the emitter connection, the transistor 27 is turned on. In present day transistors, this action is substantially instantaneous.

The effect of throwing transistor 27 into conduction

is to establish direct connection between collector 29 and input terminal 11 through dropping resistor 24 and the point 26. This effectively unclamps the point 26 and reduces the voltage drop across Zener diode 23 substantially to zero. For this reason, E_4 cannot be greater than E_3 so that there is no difference signal to turn on transistor 17 and it thus remains non-conductive and is protected from overloading.

Upon termination of the short circuit condition, the transistor 27 is immediately rendered non-conductive to re-establish the reference voltage drop across Zener diode 23 and reactivate the regulatory section of the system so that transistor 17 is again effective to regulate the output voltage.

It will be noted that the effect required to turn on transistor 27 is a differential one caused by a decrease in output voltage and a simultaneous increase in output current. Under normal conditions of operation, a drop in output voltage such as is caused by a change in the value of the load 16 does not result in an increase in output current so that such normal effects which are desired to be regulated against have no effect on transistor 27 and the reference voltage E_4 across Zener diode 23 remains constant. This permits the regulating transistor 17 to operate in a normal fashion.

One suitable application for the present invention is in the regulation of a variable input voltage supplied by a Diesel locomotive engine for use in powering a two-way radio system. In a typical system of this type a D.C. input voltage of 64-80 volts is regulated to a constant value of 60 volts.

The circuit components employed had the following values:

Resistor 22	12.5 ohms.
Zener diode 23	Type HZPR-56 (60 volt drop).
Transistors 17 and 27	2N-618.
Resistor 24	1000 ohms.
Resistor 32	200 ohms.
Resistor 33	6.67 ohms.
Resistor 34	0.5 ohm.

Additional transistors may, of course, be connected in parallel with transistor 17 to increase the current range of the regulator circuit. In some commercial embodiments of this circuit two regulator transistors are used.

The present invention provides an effective protective circuit to prevent the self-destruction of voltage regulating elements, such as transistors, which may be damaged by over-loading. At the same time, the operation of the switching transistor due to a differential action enable the system to discriminate between abnormal conditions of operation, such as short circuits, and normal regulation requirements.
